UNITED STATES PATENT OFFICE

2,500,642

HEATING SYSTEM

Stanley H. Morse, Dearborn, and
Eldred E. Evans, Wayne, Mich.

Application November 9, 1945, Serial No. 627,598

4 Claims. (Cl. 237—56)

1

This invention relates to heating systems, the object being to provide a new and improved form of heating apparatus wherein radiators of a steam system or grilles or registers usually used with a hot air system may be dispensed with thus avoiding the unsightly appearance of such devices and substituting therefor a baseboard on the wall preferably at the floor line having a conduit parallel therewith through which the heating medium, such as heated gases, hot water or air, may flow from a supply source not here shown.

These and other objects and features of the invention are hereinafter more fully described and claimed and a heating system embodying our invention is shown in the accompanying drawing in which:

Fig. 1 is a perspective view showing a room having a baseboard formed with a conduit through which steam or hot water heating system is positioned.

Fig. 2 is an elevation showing the portion of the room at the floor line and means for supplying steam or hot water that may be discharged through the piping in the baseboard.

Fig. 3 is a perspective view in section showing an end of a baseboard formed to provide a conduit for the heating medium.

Fig. 4 is a similar view showing an alternative form of base.

Heretofore buildings, especially houses, have been heated by hot air furnaces requiring registers in the floor or base of a vertical wall which are unsightly and when used in the floor of a room accumulates considerable dirt and dust which is carried into the room by a flow of hot air through the register.

The invention as herein disclosed comprises a base element 1 formed of blocks of any desirable material having a lower straight edge 2 engaging the floor surface and at the upper edge is provided with an inturned flange 3 which preferably has a downturned flange 4 as shown in Fig. 3. Also, as shown in said figure, intermediate the upper and lower edges thereof, is provided a conduit 5 on the wall face of the block preferably of such width that its outer surface occupies the same plane as the outer face of the downturned flange 4. The outer face of the flange 4 and the conduit 5 is spaced from the wall of the room and a sheet of insulating material is provided between the outer face of the flange and the outer face of the conduit 5.

The heating system here shown is of a hot water or steam type showing the furnace element 7 at the base of a building wall 8 having a floor line as indicated at 9 in Figs. 1 and 2.

2

The heating system illustrated is of steam or hot water type and the pipe 10 for the hot water or steam is connected with the furnace 7 and discharges through the conduit 11 below the floor line which has conduits 12, 13, 14 connected therewith extending through the conduit 5 of the base element 1 and lead to the return line 15 connected with the furnace as at 16. Preferably a sheet of asbestos or other heat insulating material, indicated at 6, is placed on the wall surface, as shown in Fig. 3, to reduce heat transfer thereto. The pipe 13 in the conduit 5 heats the base member 1 at the floor of the room and, while I have shown a steam pipe 13 in the conduit 5, it is to be understood that heated air may be caused to flow through the passageways 5 without departing from the spirit and scope of the invention herein disclosed.

In the form of the invention shown in Fig. 4, 20 the base member is formed of a series of blocks to provide inner and outer walls 16 and 17 and forming a larger duct 18 than that shown at 5 in Fig. 3 which is especially desirable when hot air is used as a heating medium due to the greater amount 25 of surface being directly heated by the air stream.

In either form of the invention shown it is preferable to provide a heat insulating sheet 18 between the walls 17 and the wall surface engaged thereby. As here shown a finish molding 30 19 may be provided at the bottom edge of the inner wall or may be formed integrally therewith as may be desired. It is further to be understood that the base member 1 may extend outwardly into a room as shown or it may be partially or wholly set into the wall to thus conserve room space at the floor line. This position of the duct provided by the series of blocks may be above the floor line if desired and particularly in old structures the blocks may be placed in contact with the inner face of the room wall as shown 35 in Fig. 3.

A series of blocks are positioned in end to end relation providing a duct through which heated air may be discharged by means of a blower, not 40 here shown, at one end of the duct and an exhaust fan at the remote end, the air being taken from the hot air chamber of a furnace and distributed uniformly about the room and avoiding the use of hot air registers which tend to localize the 45 heat at the point of entrance of the heated air to the room.

In either of the forms of the invention shown and described heat is transferred to the room space uniformly about the entire wall surface and thereby avoiding "cold spots" in the room.

From the foregoing description it will be real-

ized that the heating system according to our invention is simple in character and provides a unique arrangement of parts and avoiding the unsightliness of radiators or registers and provides for more uniform temperature in the room.

Having thus briefly described our invention, its utility and mode of operation, what we claim and desire to secure by Letters Patent of the United States is:

1. A space heating system comprising a series of blocks in end to end relation provided on the inner face of the walls forming the space, the blocks each being provided with a transverse duct and when positioned in end to end relation providing a continuous passageway about the room, a sheet of insulating material on the face of the block in contact with the wall surface, and a pipe extending about the room in the duct, and means for causing flow of a heated fluid through the pipes.

2. A room heating system comprising a series of blocks placed in end to end relation at the floor line of the room and each formed to provide a transverse duct, heat insulating means between the inner face of each of the blocks and the wall surface tending to prevent transfer of heat directly thereto, and a conduit for the heating medium in the duct.

3. A room heating system comprising a series of blocks each having a transverse passageway and when erected providing a continuous passageway about the room at the floor line, means for supplying the passageway with heated fluid, comprising a conduit in the passageway through which heated fluid may be passed and a return conduit below the floor line, a source for supply of heated fluid to the conduit, and a return duct

connected with the end of the first named duct whereby continuous flow of heated fluid through the duct is maintained, and heat insulation means between the duct and the wall surface.

5. A room heating system comprising a series of blocks in end to end relation at the floor line of the room each formed to provide a transverse duct and when erected forming a continuous passageway about the room at the floor line, a furnace for supplying a heating medium to the duct, a pipe in the passageway connected with the furnace, and a return pipe below the floor line and discharging to the furnace whereby continuous flow of the heating medium in the passageway is provided, and heat insulating means between the duct and the wall surface.
